UNITED STATES PATENT OFFICE.

GEORGE WILLIAM HARLAN, OF OTTERVILLE, MISSOURI.

WIRE-STRETCHER.

SPECIFICATION forming part of Letters Patent No. 779,218, dated January 3, 1905.

Application filed May 17, 1904. Serial No. 208,436.

To all whom it may concern:

Be it known that I, GEORGE WILLIAM HARLAN, a citizen of the United States, residing at Otterville, in the county of Cooper and State of Missouri, have invented new and useful Improvements in Wire - Stretchers, of which the following is a specification.

My invention relates to new and useful improvements in wire-stretchers especially adapted for use in stretching wire fabric such as used in the construction of fences; and its object is to provide means whereby the fabric can be quickly and thoroughly stretched by one operator.

15 The invention consists of a pivoted lever which is adapted to be connected to a fixed post or other like object and which has oppositely-disposed hooked arms connected thereto at opposite sides of the pivot and which are normally held in proper relation to each other by a spring connecting the same.

20 The invention also consists of means for automatically moving the hooked arms into engagement with the object to be gripped thereby.

25 The invention also consists of the further novel construction and combination of parts hereinafter more fully described and claimed, and illustrated in the accompanying drawings, 30 showing the preferred form of my invention, and in which—

Figure 1 is a perspective view showing my improved wire-stretcher applied to a fence fabric. Fig. 2 is a plan view of the stretcher. 35 Fig. 3 is a section on line 3-3, Fig. 2; and Fig. 4 is a plan view of the arms and a portion of the lever, parts of said arms and the telescoping connecting-rods being shown in section.

40 Referring to the figures by numerals of reference, 1 is a lever having a socket 2 at one end, in which is arranged a handle 3. Oppositely - disposed semicircular extensions 4 are formed integral with the lever 1, and at the center of the circle formed by these extensions is a pivot-pin 5, on which is arranged a yoke 6, having a chain 7 secured to it. This chain has a hook 8 at its free end. A curved strip 9 is formed concentric with one of the extensions 4 and is connected thereto by means 45 of arms 10, and this strip 9, as well as the ex-

50 tension 4 to which it is connected, is slidably mounted within similar oppositely-disposed arms 11, having hooked claws 12 at their free ends. Screws 13 are adjustably mounted within the lever 1 at opposite ends of the strip 55 9 and are provided with thumb-nuts 14, by means of which they may be readily locked in adjusted position.

A slotted rod 15 is pivoted to one of the arms 11 and has a threaded end 16, adapted to 60 project into an oppositely-screw-threaded sleeve 17, which also engages the threaded end of a rod 18. This rod is pivoted to the other arm 11. The pins 19, forming the pivots of the rods 15 and 18, also serve as means 65 for securing the ends of a coiled spring 20 to the arms 11.

When it is desired to stretch wire fabric, strips 21, of wood or other material, are clamped on opposite faces thereof, and a chain 70 22 or other flexible object is fastened to the central portion of the strips 21. Chain 7 is then looped about a fixed post 23 and is secured in place by placing hook 8 in engagement with one of the links of the chain. 75 Chain 22 is then placed in engagement with the hooked claws 12 and the lever 1 is swung backward and forward upon its pivot-pin 5. When the lever is moved in the direction of the arrow in Fig. 2, the forwardly-extending 80 arm 11 will draw chain 22 longitudinally, while at the same time the rods 15 and 18 will swing the other arm 11 oversaid chain and over the hooked claw in front thereof and will cause the claw to contact with and automatically 85 grip the chain in advance of the first-mentioned arm 11. This automatic engagement by the claws is produced by the spring 20. It will thus be seen that the continual operation of the lever 1 will cause the chain 22 to 90 be drawn gradually toward the post 23, and therefore strips 21 will also be drawn toward it and the wire fabric connected to the strip will be pulled taut. The adjustable screws 95 13 abut against the arms 11 when lever 1 nears the limits of its movement, and therefore serve to positively move the arms 11 toward the chain 22 when the same is to be engaged thereby.

In the foregoing description I have shown 100

the preferred form of my invention; but I do not limit myself thereto, as I am aware that modifications may be made therein without departing from the spirit or sacrificing any of 5 the advantages thereof.

Having thus described the invention, what is claimed as new is—

1. The combination with a lever fulcrumed between its ends; of hooked arms pivoted to 10 the lever at opposite sides of its fulcrum, a spring connection between the arms, and means for limiting the movement of the arms in opposite directions.
2. The combination with a lever fulcrumed 15 between its ends; of hooked arms pivoted to the lever at opposite sides of its fulcrum, a spring connection between the arms, and supporting means for the arms connected to the lever.
3. The combination with a lever fulcrumed 20 between its ends; of hooked arms pivoted to the lever at opposite sides of its fulcrum, a spring connection between the arms, supporting means for the arms connected to the lever, 25 and adjustable arm-contacting devices upon the lever.
4. The combination with a lever fulcrumed at a point between its ends; of oppositely-extending arms pivoted to the lever at opposite 30 sides of its fulcrum, said arms having hooked claws, a slotted rod pivoted to one of the arms,

a rod pivoted to the other arm, an adjustable connection between the rods, and a spring connection between the arms.

5. The combination with a lever fulcrumed 35 at a point between its ends; of oppositely-extending arms pivoted to the lever at opposite sides of its fulcrum, said arms having hooked claws, a slotted rod pivoted to one of the arms, 40 a rod pivoted to the other arm, an adjustable connection between the rods, means for limiting the movement of the rods in opposite directions, and a spring connection between the arms.

6. The combination with a lever fulcrumed 45 at a point between its ends; of oppositely-extending arms pivoted to the lever at opposite sides of its fulcrum, said arms having hooked claws, a slotted rod pivoted to one of the arms, 50 a rod pivoted to the other arm and adjustably connected to the first-mentioned rod, an arm-supporting device extending from the lever, a spring connection between the arms, means for limiting the movement of the arms in opposite directions, and arm-contacting devices 55 adjustably connected to the lever.

In testimony whereof I affix my signature in presence of two witnesses.

GEORGE WILLIAM HARLAN.
